CARBURETOR

Arthur William David Gladwell, London, England

Application February 7, 1936, Serial No. 62,852
In Great Britain July 18, 1935

4 Claims. (Cl. 261—116)

This invention relates to carburetors for internal combustion engines, of the type in which the fuel is atomized with a primary supply of air at the head of a spraying nozzle and is then mixed 5 with the main air supply passing around the nozzle into a Venturi or choke tube.

According to this invention, the spraying nozzle comprises a central tube or passage for the fuel surrounded by an air passage having at its upper 10 end a perforated cap with a central divergent cavity, the fuel being delivered axially into this cavity and the air being delivered through oblique holes in the divergent walls of the cavity.

The invention is hereafter more fully described 15 with reference to the accompanying drawing, in which:—

Fig. 1 is a sectional elevation of the body or mixing chamber of a vertical carburetor according to one embodiment of the invention.

Fig. 2 is a similar view of a modification.

Fig. 3 is a plan view of the choke tube.

Fig. 4 illustrates the preferred method of making the choke tube.

Referring to Fig. 1, the carburetor comprises a 25 mixing chamber 10 having its lower portion 11 of frusto-conical shape, open to the atmosphere at the bottom and formed with a cross-bar 12 which supports the spraying nozzle 13. The upper part 14 of the mixing chamber is of cylindrical shape, provided with means, such as a flange 15, for attachment to the throttle chamber 16 leading to the engine. Inside the cylindrical upper part 14 there is mounted a choke tube 17, resting upon a 30 step 18 in the wall of the chamber, and retained 35 by the flange 19 of the throttle chamber.

The spraying nozzle comprises a cap 21 secured to the top of a central tube 22 within an outer tube 23, the latter being supported by a polygonal base 24 of which the shank 25 is screwed into a 40 hole 26 in the hollow cross bar 12 extending from one side to the other of the mixing chamber below the choke tube 17; the lower end of the mixing chamber is shown as of greater width, to compensate for the restriction formed by the cross-bar 12. Gasoline or other fuel is fed from a float 45 chamber (not shown) through a duct 27 in the cross bar 12 to a central bore 28 into which the lower end of the tube 22 is screwed or otherwise secured so as to prevent leakage of fuel at this point. A second duct 29 extending in the opposite direction along the cross bar 12 admits air at atmospheric pressure to the space around the lower end of the fuel tube 22, this air being warmed or heated if desired, for example by contact with 50 the exhaust manifold of the engine; the tempera-

ture of the air thus admitted may be from 35 to 70° C., for example, in the case of gasoline of standard quality.

The cap 21 has a central perforation 30 registering with the bore of the fuel tube 22, the parts being secured together by means of a boss 31 on the bottom of the cap; this boss is shown as being counterbored, coaxially with the perforation 30, to receive the upper end of the tube 22, which is preferably soldered in place. The exterior of the 10 cap 21 is formed with a rounded rim 32 which is shouldered down at 33 so as to fit the upper end of the outer tube 23, the cap 21 being held down on the latter by the attachment of the inner tube 22; the rim 32 produces a slight restriction of the 15 passage through the choke tube 17.

The choke tube 17 has approximately the usual venturi-shaped or convergent-divergent interior, as indicated at 34, but the passage area is controlled by the presence of steel balls 35 loosely engaged in open-sided cells or flutings 36 formed along the interior. The balls project inwardly of the choke tube, for example to the extent of one-quarter of their diameter, so as to restrict the passage area at their own level, as compared with the 20 circular or annular area of a normal choke tube of the same diameter. The flutings 36 (see Fig. 3) are preferably part-circular in cross-section, more than semi-circular in extent, and of radius slightly greater than the balls 35; their open sides, 25 towards the interior of the choke tube, afford gaps 37 slightly narrower than the diameter of the balls mounted in them. They extend longitudinally down from the top of the choke tube to the 30 level of the throat or narrowest portion 38 of the 35 interior, so that in the normal position shown in Fig. 1, with the balls resting at the bottom of the cells or flutings 36, the area of the throat is restricted by the inwardly projecting surfaces of the 40 balls; the throat 38 may comprise, as seen in Fig. 1, a short cylindrical portion between the convergent and divergent portions of the choke.

The top of the nozzle cap 21 provides a central divergent cavity 39, in the form of a shallow inverted cone, coaxial with the perforation 30, 45 the walls of this conical cavity being for example at an angle of 30° to the horizontal so as to form a sharp edge at their junction with the rim 32. Oblique holes 40, preferably three or more in number, evenly spaced round the axis, and of a 50 diameter which may be from .030 to .050 inch, for example, are formed in the divergent walls of the cavity 39, these holes connecting with the top of an annular space or chamber 41 inside the tube 23 and concentric with the fuel tube 55.

22; these holes 40 may also be inclined at an angle of 30° to the horizontal, and they are arranged in radial planes so that their axes and that of the fuel tube 22 and perforation 30 intersect at a point 42 within the cone 39. Partitions or baffles, for example of helical form, may be inserted in the annular chamber 41, as indicated at 43.

The head of the nozzle 13 extends just above the level of the throat 38, and the circumferential rim 32 of the cap 21 projects about one or two millimeters radially beyond the outer tube 23; this rim 32 lies at a slightly higher level than the restricted area provided by the projecting surfaces of the balls 35 in their normal position. When more suction is applied by the opening of the throttle, the increased flow of air through the choke tube 17 tends to lift the balls 35 inside their cells 36 and carry them along to the upper and wider part of the choke tube, thus removing the restriction from the throat and reducing its proportional effect as the balls rise towards the final position shown in dotted lines at 35a in Fig. 1. But at the initial opening of the throttle from the idling position, the lifting of the balls first carries them to the level of the rim or bead 32 at the head of the nozzle 13, thereby producing a greater restriction, and only thereafter does the passage area become increased; the effect of this initial restriction is to provide a richer mixture at the moment of opening the throttle for acceleration after a period of slow running, and thus to avoid the "flat spot" which is liable to cause engine stoppage under such conditions.

In operation, the fuel issuing from the perforation 30 will be met by the oblique streams of air drawn from the holes 40 by the injector effect of the engine suction, these streams breaking up the fuel into a fine mist (as indicated at 44) which mixes with the main air supply passing round the exterior of the nozzle 13; the atomizing air, drawn from the duct 29, will have passed through the interior of the base 24 into the annular space or chamber 41 between the two tubes 22 and 23, so that this air (if sufficiently heated) will have raised the fuel in the tube 22 to a temperature approaching or exceeding its initial boiling point, before it issues from the perforation 30, vaporization therefore taking place immediately into the main air current.

The number and size of the oblique air holes 40 may be varied; these holes have a limiting effect upon the quantity of fuel passed at high speeds, so that the fuel consumption remains approximately proportional to the power developed. The divergent cavity 39 also acts to some extent as a basin for catching drops of fuel, the sharp edge of the cap above the rim 32 preventing the fuel from dribbling down the outside of the nozzle 13 at low speeds.

In an alternative construction, the air passage to the holes 40 may be formed by a pipe coil or spiral closely surrounding the fuel tube 22 and connecting at its upper end with a perforated cap 21 screwed upon the fuel tube 22 and having a similar divergent cavity 39 with axial fuel delivery and oblique air holes.

The fuel may be supplied to the nozzle in the form of an emulsion with air by making use of the well-known system of compensating jets for feeding the fuel tube. The main air supply to the bottom of the mixing chamber may be heated if desired, particularly during cold weather, by

the same means as the atomizing air supplied to the passage 41 or by a separate heater.

Fig. 2 shows a modified construction suitable for carburetors to be fitted to relatively small engines; in this case the duct 29 for supplying atmospheric air to the nozzle 13 is dispensed with, air being admitted to the annular passage or chamber 41 from the lower part of the mixing chamber, by way of holes 45 formed in the outer tube 46. The fuel tube 22 is secured at its lower end in the center of the base 24, which thus supports the complete spraying nozzle, allowing the latter to be removed by unscrewing the base 24 from its hole in the cross bar 12.

The cells or flutings 36 in the choke tube 17 can conveniently be formed by drilling evenly-spaced oblique holes 47 into the body of a cylindrical metal blank 48, as indicated in Fig. 4; this blank is then bored out to form the convergent-divergent interior of the choke tube, as indicated by the chain-line circles 49—50 representing respectively the throat 38 and the top of the choke tube 17, thereby removing the walls of the holes 47 nearest to the axis for substantially the whole of their axial length. The choke tube 25 will then appear as shown in Fig. 3, with the open-sided cells or flutings 36 each adapted to receive one ball. With a choke-tube having a 24 millimeter throat and an internal diameter of 28 millimeters at the top, there may be employed 30 nine balls each $\frac{1}{4}$ inch in diameter, fitted in cells or flutings formed by drilling holes of $\frac{3}{2}$ inch diameter at an obliquity of $6\frac{1}{2}$ degrees to the axis, corresponding to the divergent side of the choke, the pitch circle of the balls varying by 35 about 3 millimeters in diameter with an axial movement of about $\frac{1}{2}$ inch between their extreme positions. When fully raised, the balls will be retained by the connecting flange or facing 19 to which the carburetor body is secured, so that 40 they cannot slip out of place.

It will be understood that the invention is not limited to the use of steel balls as displaceable elements controlling the passage area through the choke tube 17, and that it may be applied to 45 carburetors of other types than that above described, for example to carburetors having the axis of the choke tube 17 and spraying nozzle 13 inclined to the vertical; in cases where the axis approaches the horizontal position, the gravity 50 control of the displaceable elements may be supplemented or replaced by spring or like control.

What I claim is:—

1. In a carburetor having a spraying nozzle mounted coaxially within a choke, said nozzle comprising two concentric tubes, means for admitting fuel and atmospheric air respectively to the inner one of said tubes and to the annular space between said tubes, and a centrally perforated cap upon the upper ends of said tubes, a rim around said cap, said rim located above the narrowest portion of said choke and projecting radially beyond the outer one of said tubes, the upper surface of said cap including a depression around the central perforation and a plurality of 65 oblique holes spaced around said central perforation, said holes communicating with said annular space below said cap and converging upon the axis of said central perforation at a point within said depression. 70

2. In a carburetor having a spraying nozzle mounted coaxially within a choke, said nozzle comprising two concentric tubes, a cap upon the upper ends of said tubes, a rim around said cap, said rim located above the narrowest portion of 75

said choke and projecting radially beyond the outer one of said tubes, means for admitting fuel to the inner one of said tubes, and means for admitting air to the annular space between said tubes, said air-admitting means being independent of the main air supply passing externally of said nozzle, said cap having a perforation in line with said inner tube and also a plurality of converging holes extending from said annular space to the upper surface of said cap, and the air admitted to said annular space being discharged through said holes for mixture with fuel discharged through said perforation prior to meeting said main air supply passing externally of said nozzle.

3. In a carburetor having a spraying nozzle mounted coaxially within a choke through which the main air supply passes, said nozzle comprising two concentric tubes, means for admitting fuel to the inner one of said tubes, and means for admitting air at atmospheric pressure to the annular space between said tubes, and a cap surrounding said tubes, said cap including a peripheral bead of diameter greater than the exterior

diameter of the outer one of said tubes, and the upper surface of said cap being formed as a conical depression having a central perforation communicating with said inner tube and a plurality of oblique holes spaced round said perforation, said perforation being at the bottom of said depression, and said holes communicating with said annular space and converging upon the axis of said perforation at a point within said depression.

4. In a carburetor having a spraying nozzle mounted coaxially within a choke through which the main air supply passes around said nozzle, said nozzle comprising a central tube, a passage surrounding said tube, means for admitting fuel and atmospheric air to said tube and passage, and a cap surmounting said tube and passage, said cap having its upper surface formed as a conical depression with a central perforation communicating with said tube and a plurality of oblique holes communicating with said passage, and said cap including a peripheral bead located above the narrowest portion of said choke.

ARTHUR WILLIAM DAVID GLADWELL.
